UNITED STATES PATENT OFFICE.

JOHN HAUG, OF PHILADELPHIA, PENNSYLVANIA.

QUADRUPLE-EXPANSION ENGINE.

SPECIFICATION forming part of Letters Patent No. 403,266, dated May 14, 1889.

Application filed June 27, 1887. Serial No. 242,603. (No model.)

To all whom it may concern:

Be it known that I, JOHN HAUG, a citizen of the United States, and a resident of Philadelphia, Pennsylvania, have invented certain 5 Improvements in Quadruple-Expansion Engines, of which the following is a specification.

The object of my invention is to so construct a quadruple-expansion engine as to provide 10 for using the engine as a true quadruple-expansion engine, receiving live steam in the first or smallest cylinder only of the set, or as a double-compound engine, receiving live steam in both of the small cylinders. 15 In the accompanying drawings, Figure 1 is a plan view of one form of quadruple-expansion engine constructed in accordance with my invention, the intermediate or directing valve-chest being shown in section; Fig. 2, a 20 view, partly in section and partly in elevation, through one pair of cylinders and their valve-chests, the directing valve-chest being shown in elevation; Fig. 3, a view of the intermediate or directing valve-chest and its valves, 25 showing the latter in different positions from those illustrated in Fig. 1; Fig. 4, a diagram illustrating the disposal of the cylinders in respect to the crank-shaft of the engine; Figs. 5 to 8, diagrams illustrating modified arrangements of the cylinders, and Figs. 9 and 10 a modified construction of the directing-valves 30 and valve-chest for use in connection therewith.

A represents the main shaft of the engine, 35 on which are cranks B B, one of said cranks being operated by a pair of cylinders, D' D⁴, and the other crank by a pair of cylinders, D² D³, these two pairs of cylinders being arranged side by side, and each pair comprising 40 a cylinder of small diameter and a cylinder of larger diameter, the cylinders being preferably disposed as shown in the diagram, Fig. 4—that is to say, the cylinder D' of smallest diameter and the cylinder D⁴ of largest diameter forming one pair, while the cylinders D² D³ of intermediate diameter form the second pair—so that the piston area and average steam-pressure of each pair will 45 be about equal, and the application of uniform power to each crank will be insured.

As shown in Figs. 1, 2, and 4, the cylinders of each pair are arranged tandem, the smaller

cylinder being in advance, and each pair of cylinders has a common cross-head, a, the piston of the smaller cylinder of the pair having a central rod, b, while the piston of the large cylinder has side rods, b', connected to said cross-head, to which is also hung one end of the connecting-rod d, the other end of the latter being adapted to one of the cranks in 55 the usual manner.

Any desired form of valves and valve-gear may be used in connection with the cylinders, that shown in the present instance being what is known as the "Marshall gear;" but it 60 should be understood that my invention is not limited to this particular valve mechanism, nor do I claim the same.

In a quadruple-expansion engine, especially when the same is designed for use in a war- 70 vessel, it is desirable to provide for working the engine either as a true quadruple-expansion engine or as a double-compound engine, the live steam in the former case being admitted to the first or smallest cylinder of the set, 75 but in the double-compound engine being admitted to the two smaller cylinders, the quadruple principle being adopted for the sake of economy when a moderate amount of power only is needed for ordinary cruising, and the 80 engine being worked as a double-compound engine when greater power is needed for steaming at high speed in case of emergency—as, for instance, in pursuing or escaping from an enemy. For this reason I combine with the 85 four cylinders of the engine an intermediate or directing valve-chest, F, having valves and seats so arranged that the eduction pipe or passage of the first cylinder may be caused to communicate with the induction pipe or pas- 90 sage of the second cylinder, the eduction pipe or passage of the latter with the induction pipe or passage of the third cylinder, and so on; or the induction-pipes of both the first and second cylinders may be placed in communication 95 with the live-steam pipe, and the eduction-pipes of said first and second cylinders caused to communicate with the induction pipes or passages of the third and fourth cylinders, respectively. 100

As shown in the drawings, f', f², f³, and f⁴ represent, respectively, the induction pipes or passages of the cylinders D', D², D³, and D⁴, and g', g², g³, and g⁴ represent, respectively,

the eduction pipes or passages of said cylinders.

The chest F has chambers h' , h^2 , h^3 , and h^4 , communicating, respectively, with the induction pipes or passages f' , f^2 , f^3 , and f^4 , and other chambers, i' , i^2 , i^3 , and i^4 , communicating, respectively, with the eduction pipes or passages g' , g^2 , g^3 , and g^4 of the various cylinders, the chamber h' also communicating with

- 10 the live-steam-supply pipe G, while the chamber i^4 communicates with the exhaust-pipe G' , leading to the condenser. In the partition between the chambers h' and h^2 there is an opening, m , and in the partitions forming the 15 boundaries of the chambers i' , i^2 , and i^3 are openings m and m' , located opposite each other, the openings m being between the chambers i' h^3 , i^2 h^4 , and i^3 i^4 , respectively, while the openings m' are respectively between the 20 chambers i' h^2 , i^2 h^3 , and i^3 h^4 .

Passing centrally through the chest F is a valve-stem, p , which carries a single valve, n , adapted to close the opening m between the chambers h' and h^2 , and a series of duplex valves, nn' , one for each of the chambers i' , i^2 , and i^3 , these valves being adapted to close either the openings m or the openings m' of said chambers, according to the adjustment of the stem p .

- 25 30 By this arrangement it will be observed that when the valves are adjusted to the positions shown in Fig. 1, so as to close all of the openings m , the chamber h' , which communicates with the live-steam-supply pipe G, is cut off from all the pipes or passages, except the pipe f' of the first cylinder, D' , the eduction-pipe g' from this cylinder being in communication through the chambers i' h^2 with the induction-pipe f^2 of the second cylinder, D^2 , the eduction-pipe g^2 of the latter communicating through chambers i^2 and h^3 with the induction-passage f^3 of the third cylinder, D^3 , and the eduction-pipe g^3 of the latter communicating through the chambers 45 i^3 and h^4 with the induction-passage f^4 of the fourth and last cylinder, D^4 , the eduction-passage g^4 of which communicates through the exhaust-pipe G' with the condenser. Steam is thus worked under full pressure in 50 the first cylinder of the set, and expansively in the second, third, and fourth cylinders; but by simply shifting the valve-stem p , so as to remove the valves from the openings m and close the openings m' , as shown in Fig. 3, the 55 live-steam chamber h' is placed in communication with the induction-pipes f' f^2 of the cylinders D' D^2 , the eduction-pipe g' of the cylinder D' communicating with the induction-passage f^3 of the cylinder D^3 , the eduction-pipe g^2 of the cylinder D^2 communicating with the induction-passage f^4 of the cylinder D^4 , and the eduction-passages g^3 g^4 of said cylinders D^3 D^4 both communicating with the exhaust-pipe G' leading to the condenser, so that steam is worked under full 65 pressure in the cylinders D' D^2 , and expansively in the cylinders D^3 D^4 , thus forming,

practically, two compound engines, the first or smallest cylinder exhausting into the third, and the second cylinder into the fourth or 70 largest, so that the degree of expansion and average pressure in each of the larger cylinders will be substantially uniform.

Although I prefer to arrange all the valves n and $n n'$ on one stem, as shown and described, so that they may all be operated simultaneously, it will be evident that the valves may be carried by independent sleeves, so as to be operated separately without departing from my invention. Although I prefer also to adopt the tandem arrangement of the cylinders and the principle of direct action shown in Figs. 1, 2, and 4, the same may be modified without departing from my invention. For instance, in Figs. 5 and 6 I have 85 shown one plan, and in Figs. 7 and 8 another plan, in which the cylinders of each pair are placed side by side.

In the arrangement shown in Fig. 5 the piston-rods of the cylinders D^3 D^4 are connected to the cranks and also by links d' to the arms of beams or levers J , which are hung to suitable bearings on the frame of the engine, the other arms of said levers being connected by links d'' to the piston-rods of the 95 cylinders D' D^2 . In this case, as in the engine shown in Figs. 1 and 2, the cranks are set at an angle of ninety degrees in respect to each other; but the pistons of the cylinders of each pair move in opposite directions, as 100 will be readily understood.

In the arrangement shown in Figs. 7 and 8 the crank-shaft is at one side of the frame, and three-armed rock-levers J' are used to transmit the movement of the piston-rods to 105 the cranks, two arms of each lever being connected to the piston-rods of a pair of cylinders, and the third arm being connected to the crank.

The disposal of the cylinders, as shown in 110 Figs. 5 to 8, necessitates the making of the intermediate or directing valve-chest, F, in two parts, as shown in Figs. 9 and 10, one part containing the chambers h' h^2 i' i^2 and being located adjacent to the valve-chests of the cylinders D' D^2 , while the other part contains the chambers h^3 h^4 i^3 i^4 , and is located adjacent to the valve-chests of the cylinders D^3 D^4 . In this case pipes i' i^2 , forming continuations of the chambers i' i^2 , connect the two 120 valve-chests F, as shown.

I claim as my invention—

1. The combination, in a quadruple engine, of four cylinders of differential diameter, a live-steam inlet, an exhaust-outlet, passages 125 for connecting the cylinders either in a continuous series or in simultaneously-operating pairs, and valves for controlling the flow through said passages, all substantially as specified.

2. The combination, in a quadruple engine, of four cylinders of differential diameter, passages connecting the first and second cylinders of the set with the steam-inlet, passages

- connecting the first cylinder with the second and third, passages connecting the second cylinder with the third and fourth, passages connecting the third cylinder with the fourth and with the final outlet, a passage connecting said fourth cylinder with said final outlet, and valves for opening and closing said passages, as described, whereby live steam may be directed to the first cylinder only and 5
10 worked in the series of cylinders in succession before reaching the final outlet, or said live steam may be simultaneously admitted to the first and second cylinders, the first cylinder exhausting into the third, the second cylinder into the fourth, and the third and fourth into the final outlet, all substantially as specified. 15
20 3. The combination, in a quadruple engine, of four cylinders of differential diameter, passages for connecting the cylinders either in a continuous series or in pairs, and duplex valves located in the eduction-chambers communicating with the first, second, and third cylinders, all substantially as specified. 25
25 4. The combination, in a quadruple engine,

of four cylinders of differential diameter, passages for connecting the cylinders either in continuous series or in pairs, duplex valves located in the eduction-chambers communicating with the first, second, and third cylinders, and a single valve controlling the communication between the induction-chambers of the first and second cylinders, all substantially as specified. 30

5. The combination, in a quadruple engine, of four cylinders of differential diameter, a directing-chest having passages for connecting the cylinders either in a continuous series or in pairs, and a series of valves carried by a single stem and controlling the flow through said passages, all substantially as specified. 35 40

In testimony whereof I have signed my name to this specification in the presence of two subscribing witnesses.

JOHN HAUG.
